UNITED STATES PATENT OFFICE

1,984,795

AUTOMATIC BINDER FEED FOR CIGAR MACHINES

John F. Halstead, Brooklyn, N. Y., assignor to
International Cigar Machinery Company, a
corporation of New Jersey

Application December 19, 1933, Serial No. 703,147

55 Claims. (Cl. 131—5)

This invention relates to automatic binder feeds for cigar machines, its main object being to provide means for automatically serving the bunch binders from a magazine to the bunch rolling table, thereby greatly reducing the cost of operating the machine.

Heretofore, a separate operator was employed on each machine to stretch one binder at a time over a cutting die from which, after being cut, a transfer carried it to the rolling apron. With the present device, the magazines of a gang of cigar machines may be refilled from time to time by one operator after he has cut enough binders for the gang of machines on a separate binder cutter.

The present invention consists of a magazine in combination with a suction-supplied transfer adapted to withdraw one binder at a time from the said magazine, to stretch the same in the lengthwise as well as in the crosswise direction and in such stretched condition to deposit the same upon the apron of the rolling table.

According to whether it is desired to withdraw the binders from the bottom or from the top of the machine, this invention may be carried out in two distinct forms. In the accompanying drawings, Figs. 1 to 10 show an apparatus for automatically feeding the binders from the bottom of a magazine, and Figs. 11 to 24 a device for taking the binders from the top of one of a number of magazines, these several magazines being mounted on a turret which, each time one of the magazines has been depleted, automatically turns to bring the next magazine into operating position. While this invention relates primarily to the automatic serving of bunch binders, it is also applicable to automatically fed cigar wrappers.

In the accompanying drawings which form a part of this specification and in which like characters of reference indicate the same or like parts:

Fig. 1 is an end elevation showing the improved automatic binder feed in conjunction with a swinging rolling table and with a swinging delivery transfer, the binders being withdrawn from the bottom of the binder magazine;

Fig. 2 is a plan view of the binder feed shown in Fig. 1;

Fig. 3 is a side elevation seen from line 3—3 of Fig. 2;

Fig. 4 is a detail section view on line 4—4 of Fig. 2;

Fig. 5 is a detail sectional view on line 5—5 of Fig. 2;

Figs. 6 to 10 are plan views showing the successive steps in the operation of the device shown in Figs. 1 to 5;

Figs. 6a to 10a are side elevations of the views shown in Figs. 6 to 10, respectively;

Fig. 11 is a side elevation showing an automatic binder feed in conjunction with a stationary rolling table, the binder in this case being withdrawn from the top of one of four magazines;

Fig. 12 is an end elevation on line 12—12 of Fig. 11;

Fig. 13 is a plan view on line 13—13 of Fig. 11;

Fig. 14 is an end-elevation on line 14—14 of Fig. 11;

Figs. 15 to 18 are details showing the construction of the binder transfer and stretcher shown at 15—15 in Fig. 11;

Figs. 19 to 24 are diagrams showing the construction of an automatic locking device used in the operation of the magazine turret as shown in Figs. 19 to 21.

In carrying the invention into effect there is provided a magazine adapted to receive a stack of cut bunch binders, and means for removing the binders one by one from the stack and wrapping them about filler charges. In the best constructions contemplated said means may operate to remove binders from the bottom of the stack or from the top of the stack, and may include an oscillatory bunch rolling table and a rotary suction cylinder operating to withdraw a binder from the bottom of the stack and carry the binder into contact with the table, or it may include a stationary bunch rolling table and a swingable binder transfer operating to pick up a binder from the top of the stack and lay it on the table. In the best constructions a plurality of the magazines may be slidably mounted on a turret for vertical movement thereon and be periodically raised step by step to bring the top binder of the stack at the binder feeding station into contact with the binder transfer, the turret being automatically turned to bring the next magazine up to the binder feeding station whenever the magazine at the binder feeding station is depleted. These various means and parts may be widely varied in construction within the scope of the claims for the particular devices selected to illustrate the invention are merely illustrative of the many possible concrete embodiments of the same. The invention, therefore, is not to be restricted to the specific constructions shown and described.

Referring to Figs. 1 to 5, in which the maga-

zine 25 containing the cut binders B is suspended above the binder feed transfer, the base 26 of the binder feed is mounted on a pedestal 27 which carries a cam-shaft 28 and a fulcrum 29 which is attached to a bracket 30 supporting a fulcrum 31 for the swinging arm 32 of an oscillating bunch rolling table 33 and a fulcrum 34 for the swinging arm 35 of a delivery transfer 36.

10 The base 26 is equipped with horizontal runways 37 upon which rests a slide 38. The slide 38 carries a series of rollers 39, 39', 39'' and has a bracket 40 in which is fixedly mounted a horizontal shaft 41 at right angles to the runways 37. On shaft 41 is movable a slide 42 guided by a key 43 on the shaft 41 fitting a groove in the slide. The slide 42 carries a bar 44 engaging with a groove in a collar 45 affixed to a shaft 46 slidably and turnably mounted in a pair of integral bearing brackets 47 and 47' swingably mounted on shaft 41. A reduced portion of shaft 46 has mounted thereon the collars 48 and 49 of the hollow binder transfer cylinder 50. The collar 48 is loose and is held against the face 25 of a gear wheel 51, which is splined to the unreduced portion of shaft 46 by a key 52 carried by it and fitting a keyway in the shaft 46, by the action of a coil spring 53 seated against a stop 54 on shaft 46. The collar 49 is fast on shaft 30 46, and the shell of cylinder 50, which has several rows of suction holes 55, is made in two parts with a telescope joint 56. The interior of roller 50, through openings in the web of collar 49, communicates with a suction head 57 turnably 35 held on the end of shaft 46 by a collar 58 and connected with the suction system of the machine by a flexible hose 59. The suction system may be of any well known construction operating to intermittently apply suction to the roller 40 50.

40 The rollers 39, 39', 39'' are arranged in two closely spaced groups, with the transfer roller 50 occupying the space between these groups. One group 39, 39', which normally supports the 45 binders B in magazine 25, extends over a length somewhat greater than the length of the binders B, and each roller has a length somewhat greater than the width of the binders B. The other group, 39'', upon which the binder stack rests 50 in the foremost position of slide 38, contains one roller less, as the suction cylinder or transfer roller 50 whose top is normally aligned with the tops of rollers 39, 39', 39'' in its pick-up position also acts as a support roller. The innermost 55 support roller 39' of the first mentioned group, nearest to roller 50, is made with a fluted periphery and has longitudinally spaced annular grooves into which extend the points of fingers 60, Fig. 4, pivoted on eccentric trunnions 61 of 60 a shaft 62 and guided by links 63 swinging on a shaft 64. The shafts 62 and 64 are supported on slide 38, shaft 62 carrying a friction roller 65 which, for a short distance before and after the roller 50 arrives in pick-up position, contacts 65 with a high speed friction pulley 66 mounted on a stud in base 26 and driven by a belt from the main drive of the cigar machine, thereby causing the finger points to move in the path shown by dotted lines and project slightly above the 70 periphery of roller 39'. This motion of the fingers 60 on the forward stroke of slide 38, agitates and loosens the lowermost binders in magazine 25 so that only one binder is withdrawn by roller 50, and, on the back stroke, the 75 oscillating fingers hit and push up the forward

edge of the next binder, thereby preventing the tips of the lowermost remaining binders from entering the space between rollers 39' and 50 which would cause the same to be folded up to a greater or less extent by the subsequent rearward motion of slide 38.

5 The shafts of rollers 39, 39', and 39'' carry gears 67 meshing with a stationary rack 68 supported by brackets 69 attached to base 26 to rotate the rollers during the reciprocation of slide 42 and thus smooth the lowermost binders in magazine 25. The gear 51 on shaft 46 meshes with a gear 70 turning on a stud in bearing bracket 47, the gear 70 in turn meshing with a gear 71 loose on shaft 41 and in engagement with a movable rack 72 slidably mounted in brackets 73 attached to the rack 68. The rack 72 remains stationary during the motion of slide 38, thereby causing the roller 50 to revolve in unison with the rollers 39, 39', 39'', and, upon the return 20 of roller 50 to its starting position, is reciprocated by a gear segment 74 fulcrumed in a lug 75 of base 26 and connected by a link 76 with a cam lever 77 fulcrumed on shaft 29 and actuated by a cam 78 on shaft 28 (Fig. 2).

25 The bearing bracket 47 carries a pedestal 79 in which is mounted a roller 80 resting on rack 68 thereby keeping the top of roller 50 in alignment with the tops of rollers 39, 39', and 39''. In line with the starting position of roller 50, 30 the rack 68 has a circular depression 81, Fig. 5, into which the roller 80 drops and thus causes the shaft 46 with roller 50 to swing downwards about shaft 41 unless a cam slide 82 moving on pins 83 in rack 68 is in position to support roller 35 80 and thus to prevent it from entering said depression. The cam slide 82 for this purpose is equipped with a pin 84 adapted to engage with either of two pins 85, 85', carried by rack 72, the forward stroke of rack 72 moving the slide 82 40 away from depression 81, and the back stroke moving it into registration therewith. As stated above the motion of rack 72 is timed in relation to that of slide 38 which latter is effected by a link 86 attached to a lug 87 on the slide and 45 pivoted to a cam lever 88 fulcrumed on shaft 29 and operated by a second track of cam 78 (Fig. 2).

40 For the purpose of transferring the binder B withdrawn from magazine 25 by the roller 50 50 in registration with the width of the bunch rolling table 33, the slide 42 is moved inward on shaft 41 by a link 89 pivoted to a lever 90 pinned to a shaft 91 supported by bracket 47. The shaft 91 is actuated through a connecting rod 55 94 by a cam lever 95 fulcrumed on shaft 29 and having a roller 96 in engagement with a cam 97 on shaft 28 (Fig. 1). As the shaft 46 is moved inward when transferring the binder B, the collar 49 moves with it while the collar 48 is held back by the spring 53 until the unreduced portion of shaft 46 has come in contact with its hub, thus opening the joint 56 by the amount of this lost motion and stretching the binder B on roller 50 by a like amount.

65 In Figs. 6 to 10 and 6a to 10a the operation of the device shown in Figs. 1 to 5 is diagrammatically indicated. Figs. 6 to 10 at the left are top views and Figs. 6a to 10a at the right are side elevations, the successive motions being indicated by arrows and numbered from 1 to 20, as follows:

70 *Motion 1. (Figs. 6 and 6a)*

75 Suction roller 50 moves forward to magazine 75

25. This motion is produced by forward motion of slide 38 by cam lever 88. At the beginning of the stroke, the forward rollers 39 and 39' and, at the end of stroke, the rear rollers 39'' and the suction roller 50 support the binder stack in magazine 25.

Motion 2. (Figs. 6 and 6a)

10 During motion 1, suction roller 50 revolves in a backward direction, due to engagement of gear 71 with the then stationary rack 72.

Motion 3. (Figs. 6 and 6a)

15 During motion 1, rollers 39, 39' and 39'' also revolve in a backward direction due to engagement of gears 67 with stationary rack 68.

Motion 4. (Figs. 7 and 7a)

20 Suction roller 50 is moved back to starting position by the return stroke of slide 38 produced by cam lever 88. Suction in hose 59 is turned on full, remaining on until the beginning of motion 11 during which it is gradually turned off.

Motion 5. (Figs. 7 and 7a)

25 During motion 4, suction roller 50 revolves in a forward direction thereby drawing the binder B from the bottom of the stack and rolling it upon the roller, gear 71 being revolved by rack 72 while the latter is at rest and thus causing the rotation of roller 50.

Motion 6. (Figs. 7 and 7a)

30 During the return stroke of the slide 38, supporting rollers 39, 39' and 39'' revolve in a forward direction due to engagement of gears 67 with stationary rack 68.

Motion 7. (Fig. 8)

40 Suction roller 50 with binder B moves out over rolling table 33 due to the inward motion of slide 42 produced by cam lever 95. At the beginning of this motion, roller 50 expands longitudinally (due to spring 53) thereby stretching binder B in a crosswise direction.

Motion 8. (Figs. 8 and 8a)

45 During motion 7, suction roller 50 is turned in a backward direction by the forward stroke of rack 72 caused by gear segment 74 and cam lever 77, to move the inner end of binder B into position to meet rear end of rolling table 33 adjacent which the cigar filler F is subsequently delivered to the bight of rolling apron A, as shown in Fig. 9a.

Motion 9. (Figs. 8 and 8a)

50 Rolling table 33 starts its forward stroke which is produced by forward motion of connecting rod 98 actuated by cam lever 99 on shaft 29 due to roller 100 engaging with cam 101 on shaft 28. See Fig. 1.

Motion 10. (Figs. 8 and 8a)

65 Roller 50, with the binder B in correct position, moves down onto table 33 when the latter has moved slightly past center of roller 50. The downward motion of roller 50 is produced at the end of the forward stroke of rack 72 by pin 85 shifting the slide 82 into its "out" position, thus permitting the roller 80 to drop into the depression 87.

Motion 11. (Figs. 9 and 9a)

75 Roller 50 turns in a backward direction to un-

roll binder B upon apron A on table 33. During this motion, which is produced through rearward movement of rack 72 by gear segment 74, suction in roller 50 being gradually reduced and that supplied to table 33 by pipe 102, Fig. 5 1, being turned on.

Motion 12. (Figs 9 and 9a)

10 Simultaneously with motion 11, table 33 completes its forward stroke, the cam lever 99 moving the table 33 slightly faster than the peripheral speed of roller 50 in order to stretch the binder B in the lengthwise direction.

Motion 13. (Fig. 9a)

15

Filler charge F is deposited into loop of apron A by downward motion of a filler transfer, not shown.

Motion 14. (Fig. 9a)

20

Rolling apron A is tightened by an apron tightening device, not shown, to bring filler charge F into position for rolling.

Motion 15. (Fig. 10a)

25

Roller 50, with suction off, moves up to clear the table 33, the pin 85' shifting slide 82 back into "in" position at end of the back stroke of rack 72 and thereby raising the bracket 47 with the roller 50.

Motion 16. (Fig. 10)

30

Roller 50 moves back into original position in line with magazine 25, due to rearward motion of slide 42 imparted by cam lever 95.

35

Motion 17. (Figs. 10 and 10a)

40

During motion 16, rack 72 turns roller 50 back by the same amount it was turned forward during motion 8.

Motion 18. (Figs. 10 and 10a)

45

Table 33 starts its backward stroke, whereby apron A and the stationary rolling pin P roll filler charge F into binder B.

Motion 19. (Figs. 6 and 6a)

Table 33 completes its backward stroke.

Motion 20. (Fig. 6a)

50

Rolled bunch B F is discharged from apron A into the grippers of delivery transfer 36, which, actuated by a link 103 connecting cam lever 99 with transfer arm 35, follows the table 33 until arrested in proper position by a stop screw 104 55 engaging with a boss 105 on arm 32 and by a roller 106 engaging with a stop 107 attached to pedestal 27. See Fig. 1.

The corrective motions 8 and 17 may be eliminated by correspondingly increasing the amplitudes of motions 1 and 4, respectively, which, however, would necessitate longer cam levers and actuating links for slide 38 and rack 72, longer base 26 and stationary rack 68, and additional rollers 39 and 39'' for supporting the binder 65 stack during the motion of slide 38.

Referring now to Figs. 11 to 18, in which a binder transfer with a two-way expansible suction head picks up the binders B from the tops of a number of magazines carried by a turret 70 and deposits the same upon a stationary rolling table, the rolling table 110 is of well known construction and forms part of a pedestal 111 on which is mounted a stand 112 supporting parallel arms 113 and 114 for swinging the binder 75

transfer 115, and to which are attached brackets 116, 117, 118, 119 and 120 supporting the turret 121 with its magazines 122 and the magazine-operating and turret-indexing devices.

5 The binder transfer consists of an octagonal transfer head 115 attached to a vertical tube 123 slidably mounted in a sleeve 124 having a circumferential slot engaging with an eccentric roller 125 on a horizontal shaft 126 journaled in a bracket 127 of head 115. In the binder picking position of the binder transfer, the center of the eccentric roller 125 is disposed in the vertical plane passing through the center of shaft 126 at a distance above the shaft center equal 10 to the eccentricity of the roller. The bracket 127 carries a second shaft 128, the shafts 126 and 128 being fixed in the parallel arms 113 and 114. The arms 113 and 114 are fast on a pair of shafts 129, turning in stand 112 and having 15 gears 130 in engagement with a rack 131 guided by a roller 132 and actuated by a cam lever 133 fulcrumed on shaft 134 and having a cam roller 135 engaging with a cam 136 on shaft 137 which is driven from the main drive of the cigar machine, as hereinafter described. The action of cam lever 133 thus swings the arms 113 and 114 into the dotted positions 113' and 114' shown in Fig. 11 and at the same time reverses the position of roller 125 and thus depresses the 20 sleeve 124 by double the amount of eccentricity of the roller 125.

To horizontal studs 138 slidably carried in bearings of transfer head 115, Figs. 15 to 18, are fastened four suction heads 139 each having a lug 140 connected by a link 141 to a lug 142 on sleeve 124. The downward motion of sleeve 124 relative to tube 123 causes the studs 138 with the suction heads 139 to move outward diagonally as shown in dotted lines in Fig. 18, thereby 25 stretching the binder B carried by them in the lengthwise as well as in the crosswise direction. The tube 123 is connected by a flexible pipe 143 with the suction system of the cigar machine which through a tube 144 also supplies suction 30 to rolling table 110. The transfer head 115 has four apertures 145 each of which registers with an opening 146 in one of the suction-heads 139 which in turn have suction holes 147 in their binder contacting bottom surfaces.

35 The binders B are stacked to within a given maximum height upon the magazines 112 having vertical studs 148 sliding in bearings of turret 121 and having at their ends rollers 149 which, in their operating position, rest on a platform 150 attached to a plunger 151 connected by a link 152 at its lower end to a lever 153 pivoted on a stud 154 in bracket 119 and carrying an adjustable weight 155 which pushes 40 plunger 151 upward and raises platform 150 with the magazine 122 resting upon it.

To control this action of weight 155, the plunger locking device shown in detail in Figs. 23 and 24 is provided. Bracket 118 has two spaced bearings 156 for plunger 151 in the space 45 between which is mounted a collar 157 prevented from turning by a key 158 slidable in a keyway of plunger 151. The bore of collar 157 is larger than the diameter of plunger 151, and the collar is pressed into clamping position 50 against one side of the plunger by a spring 159, on the opposite side of which a roller 160, eccentrically mounted on the fulcrum stud 161 of a lever 162, bears against the periphery of collar 157 and upon downward movement of lever 162 counteracts the pressure of spring 159

and releases plunger 151. The lever 162 is held in its upper or noncounteracting position by a spring 163 attached to pedestal 111 and at its outer end carries two concentric rollers 164, Fig. 13, one of which engages with a cam 165 on shaft 166 while the other is in the path of a cam lever 167 fulcrumed on a stud 168 and having a cam roller 169 in engagement with a cam 170 on shaft 137. The cam 165 is intermittently driven by a worm wheel 171 on shaft 166 and 10 during the idle position of cam 165 the lever 162 is free to move from one extreme position to the other and is depressed by the motion of cam lever 167, the latter performing one such movement in each cycle in synchronism with 15 the motion of rack 131 produced by cam lever 133. Thus, each time the transfer 115 is swung into pick-up position over the binder magazine 122, the lever 162 is depressed by cam lever 167 so that the weight 155 can raise the plunger 20 151 and bring the top binder B into contact with the suction heads 139 of the transfer.

On shaft 137 there is also mounted a bevel gear 172 in mesh with a pinion 173 loose on a shaft 174 which is supported in brackets 117 and 120, and on shaft 174 is mounted a worm 175 meshing with worm wheel 171 on shaft 166 and a worm 176 meshing with a worm wheel 177 on a shaft 178 supported in bracket 117. Pinion 173 carries a jaw clutch member 179 and 25 on shaft 174 is splined a sleeve 180 provided with a jaw adapted to engage clutch member 179 and thereby to drive shaft 174. The sleeve 180 is controlled by a fork 181 which carries a pin 182 with which the hook 183 pivoted on 30 bracket 120 is normally held in engagement by a tension spring 184. An arm 185 extending from the fulcrum of hook 183 is connected by a rod 186 with a bell-crank lever 187 pivoted on bracket 118 in such a position that a stop screw 40 188 carried in a lug 189 on plunger 151 will engage with and tip the lever 187 at the end of its upward travel and thereby turn the hook 183, thus releasing the pin 182. The fork 181 shifts the clutch member 180 into engagement with 45 the clutch member 179 when the pin 182 is not held by hook 183, the fork being swung on its fulcrum 190 in bracket 120 by a cam lever 191 connected to an arm projecting from its hub by a link 192 and having a roller 193 held against 50 a cam piece 194 on gear 172, by a spring 195 (Figs. 14, 19, and 20) whereby the spring will yield to permit swinging of the cam lever 191 by cam 194 while the pin 182 is blocked by hook 183. The lever 191 is fulcrumed on a stud 196 55 in pedestal 111 on which is also fulcrumed a cam lever 197 having a roller 198 in engagement with a second cam track 199 of cam 165 on shaft 166. The free end of lever 197 carries a stud 200 engaging with a slot in a vertical bar 201 60 attached to a lug on platform 150. The lever 197 remains stationary while the link 201, during the gradual depletion of the binder stack on the magazine on platform 150, travels upward, and upon depletion, when the shaft 174 65 is thrown into rotation by the engagement of the clutch members 179 and 180, the turning of cam 199 causes stud 200 to descend, thereby pulling platform 150 down into starting position, ready to receive the next magazine of turret 70 12. (See Figs. 19, 20 and 21).

The turret 121, which is mounted on a vertical shaft 202 supported in bracket 117, is at its bottom provided with projections 203 at 90 degree intervals so arranged as to form radial 75

runways for the rollers 204 carried by a horizontal indexing wheel 205 on shaft 178 eccentric to the turret. This wheel, which is driven by worm 176 on shaft 174, during the turning period of the latter makes three-quarters of a turn corresponding to a quarter-turn of the turret, as shown in Fig. 22; each roller entering a runway and turning the turret through a quarter-turn, remaining in the runway at the end of three-quarters of a revolution of the wheel, while the next roller enters the next runway, whereby the turret is locked.

The operation of the device shown in Figs. 11 to 18 is as follows: While one of the magazines 122 is in binder feeding position, weight 155 pushes up plunger 151 at each turn of cam 170 at the moment when the binder transfer 115 is in receiving position, cam 170 unlocking clamp 157 by actuating cam lever 167 to depress lever 162. Before transfer 115 removes the top binder B from the stack, cam 170 raises lever 167 and thus permits collar 157 to relock plunger 15. See Fig. 19. When the last binder is being taken from the magazine, stop screw 188 tips lever 187, Fig. 20, thereby releasing hook 183, so that the slide 180 is then only held by engagement of cam piece 194 with roller 193. As soon as cam piece 194 has turned out of engagement with roller 193, simultaneously with raising of lever 167 by cam 170, the jaw on slide 180 is moved by lever 191 and link 192 into engagement with jaw clutch member 179, Fig. 21, thereby turning shaft 174, the worms 175 and 176 of which then revolve the worm wheels 171 and 177. The wheel 171 actuates cam 165, one track 199 of which, by means of cam lever 197, pulls plunger 151 into its starting position, while the other track 165 unlocks the plunger clamp 157. At the same time, worm wheel 177 turns indexing wheel 205, thereby removing the depleted magazine and advancing the next full magazine into feeding position on platform 150 which now again is in its lowermost position. As the plunger 151 descends, the release of lever 187 by the descent of screw 188 permits the spring 184 to pull hook 183 into holding position, ready to engage pin 182 of slide-fork 181 as soon as the next engagement of cam piece 194, immediately upon completion of the indexing motion of wheel 205, actuates lever 191 which pulls the jaw on slide 180 out of engagement with clutch member 179. The re-engagement of pin 182 on slide 180 by hook 183 keeps the shaft 174 at rest during the subsequent turning of shaft 137, the movement of lever 191 by its periodic engagement with cam piece 194 during the gradual depletion of magazine 122 being absorbed by link 192.

What is claimed is:

1. In a cigar machine, the combination with a magazine adapted to receive a stack of cut bunch binders, of means for removing the binders one by one from said stack and wrapping them about filler charges, said means operating to remove the binders from the bottom of said stack.

2. In a cigar machine, the combination with a magazine adapted to receive a stack of cut bunch binders, of means for removing the binders one by one from said stack and wrapping them about filler charges, said means including a bunch rolling table, a rotatable suction cylinder, mechanism for moving said cylinder sidewise under said stack to remove a binder therefrom, and a device for moving said cylinder to bring the binder into registry with said table.

3. In a cigar machine, the combination with a magazine adapted to receive a stack of cut bunch binders, of means for removing the binders one by one from said stack and wrapping them about filler charges, said means including a bunch rolling table, and a binder transfer operating to transfer a binder from said stack to said table and stretch it in transit. 5

4. In a cigar machine, the combination with a magazine adapted to receive a stack of cut bunch binders, of means for removing the binders one by one from said stack and wrapping them about filler charges, said means including a binder transfer operating to transfer a binder and stretch it in transit. 10

5. In a cigar machine, the combination with a magazine adapted to receive a stack of cut bunch binders, of means for removing the binders one by one from said stack and wrapping them about filler charges, said means including a bunch rolling table, and a swingable binder transfer operating to pick up a binder from the top of said stack and stretch it and lay it on said table in stretched condition. 15

6. In a cigar machine, the combination with a magazine adapted to receive a stack of cut bunch binders, of means for removing the binders one by one from said stack and wrapping them about filler charges, said means including a binder transfer operating to transfer the binder and stretch it in a lengthwise and crosswise direction. 20

7. In a cigar machine, the combination with a magazine adapted to receive a stack of cut bunch binders, of means for removing the binders one by one from said stack and wrapping them about filler charges, said means including an oscillatory bunch rolling table, and a rotatable suction cylinder operating to withdraw a binder from the bottom of said stack and move it into registry with said table. 25

8. In a cigar machine, the combination with a magazine adapted to receive a stack of cut bunch binders, of means for removing the binders one by one from said stack and wrapping them about filler charges, said means including an oscillatory bunch rolling table, and a rotatable suction cylinder operating to withdraw a binder from the bottom of said stack and deposit its outer end on said table, the cylinder thereupon rotating with a peripheral speed less than that of the table, whereby the forward movement of the table will strip the binder from said cylinder and stretch it lengthwise. 45

9. In a cigar machine, the combination with a magazine adapted to receive a stack of cut bunch binders, of means for removing the binders one by one from said stack and wrapping them about filler charges, said means including an oscillatory bunch rolling table, and an axially expansible rotary suction cylinder operating to withdraw a binder from the bottom of said stack, stretch it crosswise and deposit its outer end on said table, the roller thereupon rotating with a peripheral speed less than that of the table, whereby the forward movement of the table will strip the binder from said roller and stretch it lengthwise. 50

10. In a cigar machine, the combination with a magazine adapted to receive a stack of cut bunch binders, of means for removing the binders one by one from said stack and wrapping them about filler charges, said means including a reciprocable slide, a group of rollers on said slide normally supporting the stack of binders 70

- in said magazine, a second group of rollers and a suction cylinder also mounted on said slide, mechanism for intermittently reciprocating said slide to move the second group of rollers and 5 the suction cylinder under said stack during the forward stroke of said slide, a stationary rack geared to both groups of rollers to rotate them during the reciprocation of said slide, and a cam-operated rack geared to said cylinder to rotate it while the slide is reciprocating and while 10 the slide is stationary to cause said cylinder to withdraw a binder from said stack during the backward stroke of said slide.
11. In a cigar machine, the combination with 15 a magazine adapted to receive a stack of cut bunch binders, of means for removing the binders one by one from said stack and wrapping them about filler charges, said means including a reciprocable slide, a group of rollers on said 20 slide normally supporting the stack of binders in said magazine, a second group of rollers and a suction cylinder also mounted on said slide, mechanism for intermittently reciprocating said slide to move the second group of rollers and the 25 suction cylinder under said stack during the forward stroke of said slide, a cam-operated rack geared to said cylinder for rotating it while the slide is reciprocating and also while the slide is stationary to cause said cylinder to 30 withdraw a binder from said stack during the backward stroke of the slide, and oscillatory fingers on said slide for agitating and loosening the binders in the magazine during the forward stroke of the slide and for hitting and pushing 35 up the next binder when the lowermost binder is withdrawn by said suction cylinder.
12. In a cigar machine, the combination with 40 a magazine adapted to receive a stack of cut bunch binders, of means for removing the binders one by one from said stack and wrapping them about filler charges, said means including a bunch rolling table, a reciprocable slide, a group of rollers on said slide normally supporting the stack of binders in said magazine, a 45 second group of rollers and a suction cylinder also mounted on said slide, mechanism for intermittently reciprocating said slide to move the second group of rollers and the suction cylinder under said stack during the forward stroke of 50 said slide, a device for rotating said suction cylinder to cause it to withdraw a binder from said stack during the backward stroke of said slide, and mechanism for shifting the suction cylinder on said slide to bring the binder into registration 55 with said bunch rolling table and then lowering the cylinder to bring the binder into engagement with the table.
13. In a cigar machine, the combination with 60 a stationary magazine adapted to receive a stack of cut bunch binders, of means for removing binders one by one from the bottom of said stack and wrapping them about filler charges.
14. In a cigar machine, the combination with 65 a turret, of a plurality of magazines mounted on said turret and each adapted to support a stack of bunch binders, means for removing binders one by one from the top of the binder stack supported by one of said magazines and wrapping the binders about filler charges, and mechanism 70 for automatically turning said turret to bring the next magazine into operative relation to said means whenever the magazine at the binder feeding station is depleted.
15. In a cigar machine, the combination with 75 a turret, of a plurality of magazines mounted on said turret and each adapted to support a stack of bunch binders, means for removing binders one by one from the top of the binder stack supported by one of said magazines and wrapping the binders about filler charges, and mechanism for automatically turning said turret to bring the next magazine into operative relation to said means whenever the magazine at the binder feeding station is depleted, said means including a stationary bunch rolling table and a swingable 10 binder transfer operating to pick up a binder from the stack at the binder feeding station, stretch the binder crosswise and lengthwise, and deliver it in stretched condition to said table.
16. In a cigar machine, the combination with 15 a turret, of a plurality of magazines mounted on said turret and each adapted to support a stack of bunch binders, means for removing binders one by one from the top of the binder stack supported by one of said magazines and wrapping the binders about filler charges, and mechanism for automatically turning said turret to bring the next magazine into operative relation to said means whenever the magazine at the binder feeding station is depleted, said magazines being 20 vertically slidable in said turret, and said mechanism including a reciprocable platform arranged to support the magazine at the binder feeding station, a binder transfer swingable into a position above the stack at the binder feeding station, and a device for periodically raising said platform step by step to bring the top binders 25 of said stack into contact with said transfer.
17. In a cigar machine, the combination with 30 a turret, of a plurality of magazines mounted on said turret and each adapted to support a stack of bunch binders, means for removing binders one by one from the top of the binder stack supported by one of said magazines and wrapping the binders about filler charges, and mechanism 35 for automatically turning said turret to bring the next magazine into operative relation to said means whenever the magazine at the binder feeding station is depleted, said magazines being vertically slidable in said turret, and said mechanism including a reciprocable platform arranged to support the magazine at the binder feeding station, a binder transfer swingable into position above the stack at the binder feeding station, a device for periodically raising said platform step 40 by step to bring the top binder of said stack into contact with said transfer, and turret indexing mechanism controlled by said device to turn said turret when the magazine at the binder feeding station is depleted and bring the next magazine 45 up to the binder feeding station.
18. In a cigar machine, the combination with 50 a magazine adapted to receive a stack of cut bunch binders, of a binder transfer for removing binders one by one from the bottom of said stack, said transfer including an axially expandable rotary suction cylinder adapted to withdraw a binder from the bottom of said stack and stretch it crosswise.
19. In a cigar machine, the combination with 55 a magazine adapted to receive a stack of cut bunch binders, of a binder transfer for removing binders one by one from the bottom of said stack, said transfer including a reciprocable slide, a group of rollers on said slide normally supporting the stack of binders in said magazine, a second group of rollers and a suction cylinder also mounted on said slide, mechanism 60 for intermittently reciprocating said slide to move the second group of rollers and the suction 70 cylinder to withdraw a binder from the bottom of said stack.

cylinder under said stack during the forward stroke of said slide, and a device for rotating said suction cylinder to cause it to withdraw a binder from said stack during the backward stroke of said slide.

20. In a cigar machine, the combination with a magazine adapted to receive a stack of cut bunch binders, of a binder transfer for removing binders one by one from the bottom of said stack, said transfer including a reciprocable slide, a group of rollers on said slide normally supporting the stack of binders in said magazine, a second group of rollers and a suction cylinder also mounted on said slide, mechanism for intermittently reciprocating said slide to move the second group of rollers and the suction cylinder under said stack during the forward stroke of the slide, a device for rotating said cylinder to cause it to withdraw a binder from said stack during the backward stroke of said slide, and oscillatory fingers on said slide for agitating and loosening the binders in the magazine during the forward stroke of the slide and hitting and pushing up the next binder when the lowermost binder is withdrawn by said suction cylinder.

21. In a cigar machine, the combination with a magazine adapted to receive a stack of cut bunch binders, of a binder transfer for removing binders one by one from the bottom of said stack, said transfer including a reciprocable slide, a group of rollers on said slide normally supporting the stack of binders in said magazine, a second group of rollers and a suction cylinder also mounted on said slide, mechanism for intermittently reciprocating said slide to move the second group of rollers and the suction cylinder under said stack during the forward stroke of said slide, a device for rotating said suction cylinder to cause it to withdraw a binder from said stack during the backward stroke of the slide, and mechanism for shifting the suction cylinder axially on said slide and then lowering the cylinder to bring the binder into delivery position.

22. In a cigar machine, the combination with a magazine adapted to receive a stack of cut bunch binders, of a binder transfer for removing binders one by one from the top of said stack, said binder transfer including a hollow transfer head, a stand, a pair of parallel arms swingably mounted on said stand and pivotally connected to said transfer head, a tube fitted into said transfer head, the bore of said tube communicating with the interior of said transfer head, a circumferentially grooved sleeve mounted on said tube, an eccentric fixedly connected to the outer end of one of said arms and disposed in the groove in said tube, suction heads slidably mounted in said transfer head, the bottom of said suction heads being provided with suction holes and the interior of said suction heads communicating with the interior of said transfer head, a flexible pipe on said tube adapted to be connected to a source of suction, and a rack geared to the fulcrum of said arms, whereby movement of said rack will swing said arms and the transfer head and spread said suction heads to stretch the binder.

23. The combination with a bunch rolling table, of a binder transfer for delivering binders to said table, said transfer including mechanism for stretching the binder in transit.

24. The combination with a stationary bunch rolling table, of a binder transfer for delivering

binders to said table, said transfer including mechanism for stretching the binder lengthwise and crosswise while it is in transit.

25. The combination with a bunch rolling table, of a binder transfer for delivering binders to said table, said binder transfer including a hollow transfer head, a stand, a pair of parallel arms swingably mounted on said stand and pivotally connected to said transfer head, a tube fitted into said transfer head, the bore of said tube communicating with the interior of said transfer head, a circumferentially grooved sleeve mounted on said tube, an eccentric fixedly connected to the outer end of one of said arms and disposed in the groove in said sleeve, suction heads slidably mounted on said transfer head, the bottom of said suction heads being provided with suction holes and the interior of said suction heads communicating with the interior of said transfer head, a flexible pipe on said tube adapted to be connected to a source of suction, and a rack geared to the fulcrum of said arms, whereby movement of said rack will cause said arms to move the binder held by said suction heads into engagement with said table and stretch the binder in transit.

26. The combination with an oscillatory bunch rolling table, of an axially expansible rotary suction cylinder adapted to stretch a binder crosswise, means for moving said cylinder bodily to bring the stretched binder in contact with the table, and a device for rotating said cylinder at a peripheral speed less than that of the table during the forward movement of the latter to cause the table to strip the binder from the cylinder and stretch it lengthwise.

27. The combination with a turret, of a plurality of magazines slidably mounted on said turret for vertical movement and each adapted to support a stack of bunch binders, a binder transfer for removing binders one by one from the top of the binder stack on one of said magazines, and mechanism for automatically turning said turret to bring the next magazine into operative relation to said transfer whenever the magazine at the binder feeding station is depleted.

28. The combination with a turret, of a plurality of magazines slidably mounted on said turret for vertical movement and each adapted to support a stack of bunch binders, a binder transfer for removing binders one by one from the top of the binder stack on one of said magazines, and mechanism for automatically turning said turret to bring the next magazine into operative relation to said transfer whenever the magazine at the binder feeding station is depleted, said transfer operating to stretch the binder crosswise and lengthwise.

29. The combination with a turret, of a plurality of magazines slidably mounted on said turret for vertical movement and each adapted to support a stack of bunch binders, a binder transfer for removing binders one by one from the top of the binder stack on one of said magazines, and mechanism for automatically turning said turret to bring the next magazine into operative relation to said transfer whenever the magazine at the binder feeding station is depleted, said transfer being swingable into a position above the stack at the binder feeding station, and said mechanism including a vertically reciprocable platform arranged to support the magazine at the binder feeding station, and a device for periodically raising said platform step by step.

- to bring the top binder of said stack into contact with said transfer.
30. The combination with a turret, of a plurality of magazines slidably mounted on said turret for vertical movement and each adapted to support a stack of bunch binders, a binder transfer for removing binders one by one from the top of the binder stack on one of said magazines, and mechanism for automatically turning said turret to bring the next magazine into operative relation to said transfer whenever the magazine at the binder feeding station is depleted, said transfer being swingable into a position above the stack at the binder feeding station, and said mechanism including a reciprocable platform arranged to support the magazine at the binder feeding station, a device for periodically raising said platform step by step to bring the top binder of said stack into contact with said transfer, and turret indexing mechanism controlled by said device to turn said turret when the magazine at the binder feeding station is depleted and bring the next magazine up to the binder feeding station.
31. A binder transfer comprising a reciprocable slide, a group of rollers on said slide normally disposed in position to support a stack of binders, a second group of rollers and a suction cylinder also mounted on said slide, mechanism for intermittently reciprocating said slide to move the second group of rollers and the suction cylinder into stack-supporting position during the forward stroke of the slide, a stationary rack geared to both groups of rollers to rotate them during the reciprocation of said slide, and a cam-operated rack geared to said suction cylinder to rotate it while the slide is reciprocating to cause the cylinder to withdraw a binder from the stack.
32. A binder transfer comprising a reciprocable slide, a group of rollers on said slide normally disposed in position to support a stack of binders, a second group of rollers and a suction cylinder also mounted on said slide, mechanism for intermittently reciprocating said slide to move the second group of rollers and the suction cylinder into stack-supporting position during the forward stroke of the slide, a cam-operated rack geared to said cylinder for rotating it while the slide is reciprocating to cause said cylinder to withdraw a binder from the stack during the backward stroke of the slide, and oscillatory fingers on said slide adapted to agitate and loosen the binders in the stack during the forward stroke of the slide and to hit and push up the next binder when the lowermost binder is withdrawn by the suction cylinder.
33. The combination with a reciprocable slide, of mechanism for reciprocating said slide, a pair of shafts mounted in said slide, fingers eccentrically mounted on one of said shafts, links connecting said fingers and the other shaft, a roller mounted on the first shaft, and a stationary driven pulley disposed in the path of said roller to engage it and thereby oscillate said fingers.
34. The combination with a reciprocable slide, of mechanism for reciprocating said slide, a suction cylinder provided with suction holes for suctionally retaining a bunch binder on the cylinder, a suction head communicating with the interior of said cylinder, and means on said slide for shifting the cylinder axially and then lowering it.

35. The combination with a reciprocable slide, of mechanism for reciprocating said slide, a suction cylinder provided with suction holes for suctionally retaining a bunch binder on the cylinder, a suction head communicating with the interior of said cylinder, and means on said slide for shifting the cylinder axially and then lowering it, said means including a stationary shaft supported on said slide, a swingable bearing bracket on said stationary shaft, a shaft slidably and turnably mounted in said bearing bracket, the suction cylinder being mounted on said shaft, a reciprocable bar slidably mounted on the stationary shaft and connected to said slide to move it axially, and a rack mounted on said slide and geared to said slide to turn said cylinder.
36. The combination with a reciprocable slide, of mechanism for reciprocating said slide, a suction cylinder provided with suction holes for suctionally retaining a bunch binder on the cylinder, a suction head communicating with the interior of said cylinder, and means on said slide for shifting the cylinder axially and then lowering it, said means including a bearing bracket connected to said slide, a shaft slidably supported in said bearing bracket, a collar fixed on a reduced portion of said shaft, a collar loosely mounted on said reduced portion, the suction cylinder being mounted on said collars and formed of two telescoping parts, a stop on said shaft between said collars, and a spring surrounding said shaft and interposed between said stop and loose collar and pressing the latter against the bearing bracket, whereby axial movement of said shaft away from the bearing bracket will slightly expand the cylinder axially to stretch the binder thereon.
37. The combination with a reciprocable slide, of mechanism for reciprocating said slide, a suction cylinder provided with suction holes for suctionally retaining a bunch binder on the cylinder, a suction head communicating with the interior of said cylinder, and means on said slide for shifting the cylinder axially and then lowering it, said means including a bearing bracket swingably supported from said slide, a shaft mounted in said bracket, the suction cylinder being mounted on said shaft, a cam-operated rack geared to said shaft, and a cam slide connected to said rack and normally disposed to support said bracket and cylinder in an elevated position, whereby actuation of the cam slide by said rack will permit said bracket to swing downwardly and thus lower the cylinder.
38. The combination with a turret, of a plurality of magazines mounted on said turret and each adapted to support a stack of bunch binders, and to be carried into binder feeding position by said turret, and mechanism for automatically turning said turret whenever the magazine at binder feeding position is depleted to bring the next magazine into binder feeding position.
39. The combination with a turret, of a plurality of magazines mounted on said turret and each adapted to support a stack of bunch binders, and to be carried into binder feeding position by said turret, and mechanism for automatically turning said turret whenever the magazine at binder feeding position is depleted to bring the next magazine into binder feeding position, said magazines being vertically slidable in said turret, and said mechanism including a reciprocable platform arranged to support the

magazine at binder feeding position, and a device for periodically raising said platform step by step to elevate the magazine.

40. The combination with a turret, of a plurality of magazines mounted on said turret and each adapted to support a stack of bunch binders, and to be carried into binder feeding position by said turret, and mechanism for automatically turning said turret whenever the magazine at binder feeding position is depleted to bring the next magazine into binder feeding position, said magazines being vertically slidable in said turret, and said mechanism including a reciprocable platform arranged to support the magazine at binder feeding position, a device for periodically raising said platform step by step, and turret indexing mechanism controlled by said device to turn said turret when the magazine at binder feeding position is depleted and bring the next magazine up to binder feeding position.

41. The combination with a turret, of a plurality of magazines slidably mounted on said turret for vertical movement and each adapted to support a stack of binders and to be carried into binder feeding position by said turret, a reciprocable platform for supporting the magazine at binder feeding position, and a device for periodically raising said platform step by step to elevate the magazine.

42. The combination with a turret, of a plurality of magazines slidably mounted on said turret for vertical movement and each adapted to support a stack of binders and to be carried into binder feeding position by said turret, a reciprocable platform for supporting the magazine at binder feeding position, and a device for periodically raising said platform step by step to elevate the magazine, said device including a plunger to which the platform is attached, a counter-weight connected to said plunger to move it upwardly, and cam-controlled mechanism for periodically locking the plunger against upward movement.

43. The combination with a turret, of a plurality of magazines slidably mounted on said turret for vertical movement and each adapted to support a stack of binders and to be carried into binder feeding position by said turret, a reciprocable platform for supporting the magazine at binder feeding position, and a device for periodically raising said platform step by step to elevate the magazine, said device including a plunger to which the platform is attached, a counter-weight connected to said plunger to move it upwardly, cam-controlled mechanism for periodically locking the plunger against upward movement, and mechanism for pulling the plunger down to starting position.

44. The combination with a turret, of a plurality of magazines slidably mounted on said turret for vertical movement and each adapted to support a stack of binders and to be carried into binder feeding position by said turret, means for periodically raising the magazine at binder feeding position step by step and returning it to starting position after it has reached its uppermost position, and turret indexing mechanism controlled by said means.

45. The combination with a turret, of a plurality of magazines slidably mounted on said turret for vertical movement, and each adapted to support a stack of binders and to be carried into binder feeding position by said turret, means for periodically raising the magazine at binder feeding position step by step and returning it to

starting position after it has reached its uppermost position, and turret indexing mechanism controlled by said means, said turret being provided with radial runways at 90 degree intervals, and said mechanism including an indexing wheel eccentric to said turret and provided with rollers at 90 degree intervals on one of its faces, each of said rollers being arranged successively to enter one of said runways, turn the turret through one quarter turn during three quarters 10 of a revolution of the wheel so that the next roller will enter the next runway, whereby said turret is locked against rotation at the end of the rotation of the wheel, and a drive controlled by said means for turning said wheel by three 15 quarters of a revolution when the magazine at binder feeding position reaches its uppermost position.

46. The combination with a turret, of a plurality of magazines slidably mounted on said turret for vertical movement, and each adapted to support a stack of binders and to be carried into binder feeding position by said turret, means for periodically raising the magazine at binder feeding position step by step and returning it to 20 starting position after it has reached its uppermost position, and turret indexing mechanism controlled by said means, said turret being provided with radial runways at 90 degree intervals, and said mechanism including an indexing 25 wheel eccentric to said turret and provided with rollers at 90 degree intervals on one of its faces, each of said rollers being arranged successively to enter one of said runways, turn the turret through one quarter-turn and leave the runway 30 at the end of three quarters of a revolution of the wheel, a driven shaft geared to said wheel, a drive shaft, a clutch member loose on said driven shaft and geared to said drive shaft, a clutch member splined on said driven shaft, a cam 40 mounted on said drive shaft, a cam lever yieldingly connected to the splined clutch member and actuated by said cam to shift it into and out of engagement with the loose clutch member, and a releasable hook normally holding the 45 splined clutch member out of engagement with the loose clutch member and controlled by said means to release the splined clutch member when the magazine reaches its uppermost position and permit the driven shaft to turn said 50 wheel through three quarters of a revolution.

47. The combination with a turret having radial runways at 90 degree intervals, of turret indexing mechanism, said mechanism including an indexing wheel eccentric to said turret and provided with rollers disposed at 90 degree intervals thereon, each of said rollers being arranged successively to enter one of said runways, turn the turret through one quarter-turn, and leave the runway at the end of three quarters of a revolution of the wheel, a driven shaft geared to said wheel, a drive shaft, a clutch member loosely mounted on said driven shaft and geared to said drive shaft, a clutch member splined on said driven shaft, a cam mounted on said drive shaft, a cam lever yieldingly connected to the splined clutch member and actuated by said cam to shift it into and out of engagement with said loose clutch member, and a releasable hook normally holding the splined clutch member out 60 of engagement with the loose clutch member.

48. The combination with a turret having radial runways at 90 degree intervals, of turret indexing mechanism, said mechanism including an indexing wheel eccentric to said turret and 70

- provided with rollers disposed at 90 degree intervals thereon, each of said rollers being arranged successively to enter one of said runways, and turn the turret through one quarter-turn during three quarters of a revolution of the wheel so that the next rollers will enter the next runway, whereby said turret is locked against rotation at the end of the rotation of the wheel, and a drive for turning said wheel by three quarters of a revolution.
49. In a cigar machine, the combination with a magazine adapted to receive a stack of cut tobacco leaf sections, of means for removing the leaf sections one by one from the stack and stretching them lengthwise and crosswise.
50. In a cigar machine, the combination with a magazine adapted to receive a stack of cut tobacco leaf sections, of means for removing the leaf sections one by one from said stack and stretching them crosswise.
51. In a cigar machine, the combination with a magazine adapted to receive a stack of cut tobacco leaf sections, of means for removing them one by one from said stack and stretching them lengthwise.
52. In a cigar machine, the combination with

a magazine adapted to receive a stack of cut bunch binders, of means for removing the leaf sections one by one from said stack and stretching them.

53. In a cigar machine, the combination with a magazine adapted to receive a stack of cut tobacco leaf sections, of means for removing the leaf sections one by one from the top of said stack and stretching them lengthwise and crosswise.

54. In a cigar machine, the combination with a magazine adapted to receive a stack of cut tobacco leaf sections, of means for removing the leaf sections one by one from the bottom of said stack and stretching them lengthwise and crosswise.

55. In a cigar machine, the combination with mechanism for wrapping tobacco leaf material about a tobacco bunch, of a magazine adapted to receive a stack of tobacco leaves, means for preparing leaves for wrapping and transferring them to said mechanism, said means including devices for removing tobacco leaves one by one from said stack and stretching them.

JOHN F. HALSTEAD.
